United States Patent

Des. 238,048
Patented Dec. 16, 1975

238,048

SWITCH COVER

Anton Bertoncel, Rua 9 de Julho 545, Sao Paulo, Brazil

Filed Apr. 18, 1973, Ser. No. 352,297

Term of patent 7 years

Int. Cl. D8—09

U.S. Cl. D8—181

FIG. 1

FIG. 2

FIG. 3

FIG. 1 is a perspective rear view of my novel switch cover;

FIG. 2 is a perspective front view of the cover shown in FIG. 1; and

FIG. 3 is a front view of the cover shown in FIGS. 1 and 2.

The appearance of the sides not shown in the drawing is identical with the appearance of the opposite sides shown in the drawing.

I claim:

The ornamental design for a switch cover, substantially as shown and described.
